WIRE CLIP FORMING AND CLOSING
MACHINE

William Alexander Harrison, Liverpool, England

Application April 14, 1938, Serial No. 202,113

5 Claims. (Cl. 140—55)

The present invention relates to a machine for forming wire clips and for securely fastening the clip around two or more elements, such as the adjacent spiral spring coils of a spring mat-tress.

According to the present invention, open loops of wire, either preformed, or formed in the machine, are passed down guides in a pair of jaws displaceable at an angle to one another in guides in the machine, whereupon the wire loop is forced down further into said jaws, so that its ends overlap whereupon they are clinched upon the two or more elements to be united, by means of a hammer plunger driven from a rotating crank or the like preferably through a spring coupling.

In a modified form of the invention, the spring coupling between the hammer plunger and the crank is retained by a stop at a point near the end of its downward travel, until towards the end of the stroke of the crank pin, when the spring energized coupling is released in order to obtain a sudden clinching of the wire loop by the hammer.

The invention is more particularly described with reference to the accompanying drawings in which:

Figure 1 is a front elevation of one form of construction, partly in section.

Figure 2 is a corresponding end view partly in section.

Figure 3 is a view corresponding to Figure 1 with the parts in a slightly different position.

Figure 4 is a rear side elevation of the machine.

Figure 5 is a plan view on the line 5,5 of Figure 4.

Figure 6 is a plan view on the line 6,6 of Figure 4.

Figure 7 is a detail view of the two jaws in their withdrawn position on an enlarged scale to the preceding figures.

Figure 8 is a section on the line 8,8 of Figure 7.

Figure 9 is a section on the line 9,9 of Figure 7.

Figure 10 is a section on the line 10,10 of Figure 7.

Figure 11 is a detail of the driving mechanism.

A shaft 1 is driven from any source of power by means of a chain and sprocket drive 2, which sprocket 2 has three or more pins 3 one of which is adapted to engage with a pin 4 on a rotary sleeve 5, keyed at 6 to the shaft 1. Normally the pin 4 is withdrawn out of range of the continuously rotating pins 3 against a spring 7 by means of a lever 8, operated for instance by a

solenoid 8a, but when the lever 8 is released, the pin 4 will be projected into range of one of the pins 3, and the sleeve 5 with the shaft 1 will be rotated usually for a single revolution.

The shaft 1 (Figure 4) has a cam 9 upon it 5 engaging the tappet 10 of a lever 11 connected to one end of a chain 12, the other end of which passes over a sprocket 13 and is connected through a spring 14 to a fixed pin 15 on the frame 92. The sprocket 13 has a free wheel connection 10 with a feed wheel 17 (freely rotatable on shaft 16) in geared relationship with a second feed wheel 18 freely mounted within a bracket 19 pivoted at 20 to the frame and capable of pivoting about this pivot 20 against a spring 21. 15 Wire stock 22 can be fed through the feed wheels 17, 18 which as can be seen, will accommodate themselves to any diameter of stock. This wire is fed through a guide bush 93 detachably mounted by means of bolts 23 to the frame (when it 20 is desired to change the stock of greater or lesser diameter) the inclined edge of which 24 forms an element co-operating with a shear blade 25 carried by slide 26 moving in guides 27 on the machine, which slide has a tappet roller 28 maintained in contact with the cam 9 by means of a spring 29. The slide 26 is also provided with a U-shaped groove 30, which, moving down with the shear plate 25, bends the sheared piece of wire stock 22a into the form of a loop over the 30 bar mandrel 31. It will be noticed that the wire stock 22, 22a, is pushed over the mandrel 31 under a retaining bar 32, and against an adjustable stop 33, which sets the length of loop in conjunction with the adjustable stop 33a, acting 35 on the bracket containing the bush 93, and it will also moreover, be noticed that the wire is cut obliquely to form sharpened ends of the subsequent staple.

As the loop staple is formed it is pushed along 40 the mandrel 31 by means of a reciprocating slide 34 having a pin-and-slot connection with a pivoted arm 35, a tail projection 36 of which is engaged by a spring stop 37 on the slide member 38 having a tappet roller 39 engaging with a 45 face cam 40 on the shaft 1.

The shaft 1 also has a crank pin 41 engaging with a block 42 sliding in guides 43 in a block 44 sliding in vertical guides 45 in the machine, which block 44 has two holes 46 to receive spin-dles 47 carried upon a block 48, springs 49 being disposed between the block 48 and the block 44. 50

It will consequently be seen that as the shaft 1 rotates, the block 48 is reciprocated up and down. This block 48 carries a depending ham- 55

mer plunger 89 adapted to engage the top of the staple and drive it down inclined grooves 50, 51 in a pair of jaws 52, 53.

These jaws 52, 53 with their extensions or 5 guiding means 52a, 53a, are adapted to slide in guides at an angle to one another in the main frame 92 of the machine and the said jaws have inclined surfaces 54, 55 upon them engaged by similar inclined surfaces 58, 59 at the ends of 10 the wedging elements 80, 81 respectively, sliding in guides 45 on the frame of the machine.

These elements 80, 81 are secured at their upper ends to a bracket 82 (Figures 1 and 11), which also carries the tappet roller 39 engaging 15 with the face cam 40 on the shaft 1 through the action of the springs 61.

In the position of the parts as shown in Figure 1 it will be seen that the said cam face 40, has just 20 forced the jaws 52, 53, from the open position shown in Figure 7 to the operative or closed position, when the stop surfaces 62, 63 (Figures 1 and 3) come into contact through the inclined surfaces 58, 59 of the wedging elements 80, 81 engaging the corresponding inclined surfaces 54, 55, 25 of the jaws 52, 53.

This position will be maintained by the cam face 40 for approximately 180° movement.

Referring again to Figure 1 it will be seen that the crank pin 41 is at the top or starting 30 position and this carries the block 44 together with the block 48 (indirectly through the compression spring 61) with its depending hammer or driving element 89 downwardly into the position shown in Figure 3, whereupon the block 48 35 will normally be arrested by means of a pair of stops 67 on lever 68 pivoted at 69 and 70 to the cover plate 86. At this stage of the operation, the loop staple is partially closed round two or more elements 64, of for instance a pair of coiled 40 mattress springs 65, 66 respectively, or any other element to be connected together by clinch staples. The block 48 in moving downwards will normally be arrested by means of a pair of stops 67 on lever 68 pivoted at 69 and 70 to the frame 45 respectively, and normally held together by means of a tension spring 71 against fixed stops 90 on the cover plate 86. Further rotation of the crank pin 41 however, will cause the block 44 to descend further compressing the springs 49 and at a predetermined moment inclined stops 72 will engage 50 inclined surfaces 73 on the ends of the levers 68 forcing these apart so that the element 48 with the hammer driving element 89 is suddenly released to drive down the loop staple and clinch 55 its face most firmly around the element 64.

It will be seen from Figures 9 and 10, that the guides 50, 51 in the elements 52, 53 are slightly displaced from one another, so that the shanks of the loop pass down in planes slightly separated 60 from one another and as can be seen in Figure 10, the element 34 can only feed one loop 22 into the accommodating groove 50, 51 of the elements 52, 53 at any one time.

The beveled surfaces 60 of the block 48 engage oppositely bevelled surfaces 85 of the wedging elements 80, 81 while the cover plate 86, Figures 2, 3, completes the guiding means for the various moving parts as hereinbefore described.

The tension springs 87 secured to the frame, 70 Figures 1 and 3, and connected to the free ends of the jaw elements 52, 53 normally keep these open as shown in Figure 7. The wedging elements 80, 81 together with their terminating bracket 82, 75 carrying the roller 39, are normally forced up-

wardly by spring 61, so that the tappet roller 39 is kept in contact with the face of the cam 40.

Referring again to Figure 2 it will be seen that the bracket 82 has integral therewith a slide member 38 pivot previously described for the 5 operation of the reciprocating slide 34.

The travel of the block 44 reciprocated by the crank pin 41 is always greater than the travel of the hammer plunger 89 so that the springs 49 are compressed to a predetermined amount to act 10 upon the hammer plunger and consequently upon the clinch staple to connect a pair of coiled mattress springs 65, 66. If however, this top convolution of one or more coiled springs to be united is doubled and/or where the gauge of the wire 15 from which the springs are constructed, and also that of the clinching wire is slightly greater, then the springs 49 exert a slightly greater force upon the hammer plunger 89, without causing any undue stress upon the machine generally. 20

When wire stock of heavier or lighter gauge is required within certain limits, for the loop staple, this is readily accommodated by changing the bush bracket 93 and adjusting the spring 21. The length of the stock 22a is adjusted within certain 25 desired limits by the adjustable stops 33, 33a, while the shear blade is adjusted accordingly by the use of shims.

The bracket 94, Figures 1, 2, 7, 10 receives one loop staple from the magazine 95 when the hammer plunger 89 has been withdrawn to the position shown in Figures 1 and 2, and serves as a guiding means for the plunger 89, and the guide grooves 50a and 51a communicates with the guide grooves in the jaws 52, 53 when in the operative 35 or closed position.

It may be desired to insert a spring element between the joints 91 separating the bracket 82 and the lugs 92 on the wedging elements 80, 81 to maintain the stop surfaces 62, 63 in contact 40 during the operation of guiding and clinching the loop staple.

The end 89a of the hammer plunger 89 is shown with a spherical concave surface but in some cases it may be desired to employ a flat surface. 45

The method of operation is as follows:—

Assuming that it is required to link a pair of mattress coil springs 65, 66, by clinch staple, said springs are brought into a position located immediately below the jaw elements which are in 50 the open position shown in Figure 7.

The solenoid 8a is actuated by a suitable electrical means (not shown) whereby the lever 8 is released thus allowing the pin 4 to engage one of the pins 3. 55

Motion is thus imparted from the rotating sprocket 2 to the shaft 1 rotating said shaft as long as the lever 8 is released. Since the cycle of making and clinching a staple occupies one revolution of the shaft 1, the solenoid is adapted to release the lever 8 for a period of time equal to that taken to complete one revolution of the sprocket 2, if one staple is required at each joint. If, for instance, two staples were required at each joint then the lever 8 would have to remain 65 released for enough time to complete two revolutions of the shaft 1.

Upon initiation of movement of the shaft 1 the cams 9 and 40 begin to revolve together with the 70 crank pin 41.

The tappet 10 which is positioned above and rides against the cam 9 is raised by the cam and feeds an increment of stock through the feed wheels 17, 18 (Fig. 4) by means of chain 12 which 75

rotates sprocket 13 in free wheel connection with feed wheel 17.

This increment is fed through the guide bush 93.

5 As the cam 9 rotates further it presses tappet roller 28 downwards thereby causing the increment of stock to be cut off by the shear blade 25 and then to be bent round mandrel 31 by the U-shaped groove 30 in the slide 26.

10 The reciprocating slide 34 which is driven by the cam 40 through tappet roller 39 and member 38, then displaces the U-shaped staple along the mandrel out of range of the slide 26.

15 A plurality of staples in this condition are located along this mandrel having been produced in previous revolutions of the machine. As one is pushed out of range of the slide all the staples are displaced by an amount equal to the thickness of the stock and the staple on the end of the 20 mandrel drops into the grooves 50, 51, or the jaws 52, 53.

25 The crank pin 41 is in such a position that on delivery into the grooves this staple is immediately driven along the jaws 52, 53 by the crank operated hammer plunger 89.

30 The tappet roller 39 actuated by the cam 40 then causes the wedging elements 80, 81, to descend and thereby force the jaws downwardly together, at the same time clinching the staple 35 around the coil springs to be linked.

The chain 12 is released, causing sprocket 13 to free-wheel, the hammer 89 is raised by further rotation, the jaws open, the slide and shear blade rise, the reciprocating slide retreats, and the 35 solenoid withdraws the pin 4 from driving engagement with pins 3.

The linked springs 65, 66, are then substituted by a new pair to be linked and the cycle repeated.

40 I declare that what I claim is:—

1. A wire clip clinching machine including a frame, a pair of jaws displaceable at an angle to one another less than a right angle, guides for said jaws, guide grooves for the wire loop forming the 45 clip, a hammer plunger engaging the wire loop to displace it along the grooves in said jaws, a rotating crank driving said hammer plunger and a spring coupling interposed between said rotating crank and said hammer plunger.

50 2. A wire clip clinching machine comprising a frame, a pair of displaceable jaws having grooves therein to guide the wire clip, guides for said jaws disposed at an angle less than a right angle, a hammer plunger adapted to displace a clip in 55 grooves in said jaws, a rotating crank, a reciprocating block driven by said crank, compression springs disposed between said block and said

hammer plunger, a stop on said hammer plunger, a pair of pivoted arms, stop means on said arms and means on said block adapted to displace said arms out of range of said stop at a predetermined point in the travel of said rotating crank.

5 3. A wire clip clinching machine comprising a frame, a pair of displaceable jaws having grooves therein to guide the wire clip, guides for said jaws disposed at an angle less than a right angle, a hammer plunger adapted to displace a clip in 10 grooves in said jaws, a rotating crank, a reciprocating block, driven by said crank, compression springs disposed between said block and said hammer plunger, a stop on said hammer plunger, a pair of pivoted arms, stop means on said arms 15 and means on said block adapted to displace said arms out of range of said stop at a predetermined point in the travel of said rotating crank, step by step means feeding wire stock, a hollow guide for said wire stock having an inclined edge, a shear 20 blade co-operating with said inclined edge, means to reciprocate said shear blade from said driving crank, a mandrel, means to bend the severed piece of wire stock over said mandrel, and means to feed a bent wire clip one at a time to the 25 grooves of said jaws.

4. A wire clip clinching machine comprising a frame, a pair of displaceable jaws having grooves therein to guide the wire clip, guides for said jaws disposed at an angle less than a right angle, 30 a hammer plunger adapted to displace a clip in grooves in said jaws, said grooves being displaced progressively in differing planes, a rotating crank, a reciprocating block, driven by said crank, compression springs disposed between said block and 35 said hammer plunger, a stop on said hammer plunger, a pair of pivoted arms, stop means on said arms and means on said block adapted to displace said arms out of range of said stop at a predetermined point in the travel of said ro- 40 tating crank.

5. A wire clip clinching machine including a frame, a pair of jaws displaceable at an angle to one another less than a right angle, guides for said jaws having grooves for a wire loop forming 45 a clip, a hammer plunger adapted to displace the wire clip along the grooves in said jaws, a rotating crank driving said hammer plunger, a spring coupling interposed between said rotating crank and said hammer plunger and a stop to arrest 50 the hammer plunger against the springs of said coupling during part of the said crank and means to release the stop to give a sudden movement of the hammer plunger by reason of the release of the spring coupling.
